[57] CLAIM

The ornamental design for casket hardware, as shown and described.

DESCRIPTION

FIG. 1 is a perspective view of casket hardware, showing our new design;

FIG. 2 is a front elevational view thereof;

FIG. 3 is a side elevational view of one side thereof;

FIG. 4 is a side elevational view of the other side thereof;

FIG. 5 is a top plan view thereof;

FIG. 6 is a rear elevational view thereof; and,

FIG. 7 is a bottom plan view thereof;

FIG. 8 is a front elevational view of a second embodiment;

FIG. 9 is a side elevational view of one side thereof;

FIG. 10 is a side elevational view of the other side thereof;

FIG. 11 is a top plan view thereof;

FIG. 12 is a rear elevational view thereof; and,

FIG. 13 is a bottom plan view thereof.

The broken line showing of environment in FIGS. 1, 2 and 8 is for illustrative purposes only and forms no part of the claimed design.
